HYDRAULIC PULLER

Howard K. Nagel, Seymour, Wis.

Application May 28, 1934, Serial No. 728,018

3 Claims. (Cl. 29—86)

This invention relates to a pulling device and has as its object the provision of an efficient hydraulic puller adapted for use in the pulling of gears, wheels, pulleys and the like.

5 The invention together with its numerous objects and advantages will be best understood from a study of the following description taken in connection with the accompanying drawings wherein:

10 Figure 1 is a side elevational view of a puller embodying the features of the present invention.

Figure 2 is a fragmentary plan view of the puller.

15 Figure 3 is an enlarged sectional view through the cylinder and associated parts of the puller.

Figure 4 is a side elevational view of a slightly modified form of the invention and

15 Figure 5 is a plan view thereof.

Referring to the drawings by reference numerals it will be seen that the puller comprises a cylinder or body member 10 provided with a bore 11 in which is mounted for reciprocation a plunger 12. At one end the plunger 12 operates through a packing structure which includes a packing ring 13 of suitable fibrous material, a packing ring 14 preferably formed of brass, a packing ring 15 formed of any suitable material and a packing nut 16 that is threaded into the open end of the bore 11 of the cylinder 10.

20 At its rear end the body or cylinder 10 is suitably formed to provide a fluid chamber 17 adapted to contain, in the present instance oil. At said rear end the body 10 is also provided with an end plate 18 that forms a closure for the chamber 17 and is provided with a plug extension 19 that is accommodated within the body 10 as clearly shown in Figure 3 and is suitably formed to provide a pump chamber 20 that is connected with, and is in communication with the chamber 17 through the medium of a suitably provided passage 21. At its discharge end the pump chamber 20 opens into the bore 11 of the cylinder and is equipped with an outwardly opening spring pressed ball valve structure 22. At its intake end 25 the passage 21 is provided with an inwardly opening ball check valve structure 23.

Mounted for reciprocation within the pump chamber 20 is a pump piston 24 and this piston 24 is adapted to be reciprocated by hand through the medium of a lever 25 pivotally connected with the outer end of the piston or plunger 24 as at 26, and also pivotally connected at one end to a bracket arm 27 projecting from the end or cap plate 18.

55 From the above description it will be apparent

that the reciprocation of the pump plunger 24 will cause the oil in the chamber 27 to be pumped therefrom through the passage 21 into the pump chamber 20 and from the pump chamber into the bore 11 of the body or cylinder 10 behind the ram or plunger 12 for projecting the latter to engage with the shaft or other work with which the gear, pulley or the like to be pulled or removed is associated.

For relieving pressure behind the ram 12 the bore 11 and the chamber 17 are in communication and connected through the medium of a suitably located and formed passage 28 controlled by a needle valve 29 operable exteriorly of the body or cylinder 10.

Adjacent its forward end the body 10 is provided with a circumferentially extending groove 30 that is adapted to loosely receive a two part ring 31. The parts of the ring 31 at their meeting ends are provided with apertured lugs to accommodate securing bolts or the like 32. Each part or section of the ring is also provided with a lug 33.

For use with the puller and as shown in Figures 1 and 2 there is provided a pair of work engaging jaw members 34, and at one end the jaw members are bifurcated or otherwise formed as at 35 for pivotal engagement with the lugs 33 through the medium of rivets or other suitable means 36.

In the form of the invention shown in Figures 4 and 5 extension means are provided and the same consists of arms 37 that at one end are adapted to be pivoted to the lugs 33' of the ring 31' as at 38. At their free ends the arms 37 are connected by a ring 39 being pivoted to lugs provided at diametrically opposite sides of the ring 39 as at 40.

In this form of the invention there is also provided a pair of jaw members each of which consists of a pair of sides 41 pivotally connected to the ring 39 by rivets or the like 42. Connecting the free ends of the sides 41 is a substantially longitudinally curved or U-shaped work engaging member 43. This last form of the invention will be especially adapted for pulling or removing from the shaft or axle thereof gears, pulley wheels and the like which set too far in from the end of its axle or shaft as would not permit the use of the device when the same employs merely the jaws 34 shown in Figure 1, and also for pulling or removing gears and analogous wheels of relatively small diameter.

Having thus described my invention, what I claim as new is:

1. A puller for gears, pulleys and analogous wheels comprising a cylinder, a ram mounted for reciprocation within the cylinder, pump means provided in one end of the cylinder for forcing the fluid through the cylinder behind the ram to cause relative movement of the ram and cylinder; said cylinder being provided with an external groove, a ring engaging in the groove, arm members pivotally connected at one end to the ring at diametrically opposite sides thereof, a ring connecting the free ends of the arm members, and a pair of cooperating jaw members pivotally connected at one end with the last named ring. 5
2. A puller for gears, pulleys and analogous wheels comprising a cylinder, a ram mounted for reciprocation within the cylinder, pump means provided in one end of the cylinder for forcing the fluid through the cylinder behind the ram to cause relative movement of the ram and cylinder; said cylinder being provided with an external groove, a ring engaging in the groove, arm members pivotally connected at one end to the ring at diametrically opposite sides thereof, a ring connecting the free ends of the arm members, and a pair of cooperating jaw members pivotally connected at one end with the last named ring. 10
3. A puller for gears and analogous wheels comprising a two-diameter cylinder, a ram mounted for reciprocation within the cylinder and projectible from the cylinder at the small diameter 10 of the cylinder, pump means provided in the large diameter of the cylinder for forcing the fluid through the cylinder behind the ram to cause relative movement of the ram and cylinder, the small diameter of the cylinder being provided with a circumferentially extending external groove, a two-part ring loosely engaging in the groove, and a device for engaging the gear or analogous wheel to be pulled, said device including members disposed at opposite sides of the cylinder and pivoted at one end to the parts of said ring. 15

HOWARD K. NAGEL.
